(57) **CLAIM**

The ornamental design for a safety container, as shown and described.

DESCRIPTION

FIG. 1 is a top perspective view of our new design showing a safety container;

FIG. 2 is a top plan view of the safety container of FIG. 1; FIG. 3 is a bottom plan view of the safety container of FIG. 1;

FIG. 4 is a front end view of the safety container of FIG. 1; FIG. 5 is a rear end view of the safety container of FIG. 1; FIG. 6 is a side plan view of the safety container of FIG. 1; FIG. 7 is a side plan view of the safety container of FIG. 1, the opposite side of that shown in FIG. 6; and,

FIG. 8 is a bottom perspective view of the safety container of FIG. 1.

The broken lines in the drawings showing the safety container illustrate the portions of the safety container that form no part of the claimed design.

1 Claim, 6 Drawing Sheets(56)
